(57) **CLAIM**

The ornamental design for a waste container lid frame, substantially as shown and described.

DESCRIPTION

FIG. 1 is a perspective view of a new, original, and ornamental design of a waste container lid frame in accordance with the present invention;

FIG. 2 is a perspective view of the waste container lid frame of FIG. 1;

FIG. 3 is a front side elevation view of the waste container lid frame of FIG. 1;

FIG. 4 is a rear side elevation view of the waste container lid frame of FIG. 1;

FIG. 5 is a left side elevation view of the waste container lid frame of FIG. 1;

FIG. 6 is a right side elevation view of the waste container lid frame of FIG. 1;

FIG. 7 is a top side plan view of the waste container lid frame of FIG. 1; and,

FIG. 8 is a bottom side plan view of the waste container lid frame of FIG. 1.

The waste container shown in broken lines in FIG. 2 shows environment and forms no part of the claimed design.
